UNITED STATES PATENT OFFICE.

WILLIAM EDWARD MARSHALL AND PHILIP GEORGE PAGE McCULLOCH, OF LONDON, ENGLAND, ASSIGNORS TO NON-DAZLITE, LIMITED, OF LONDON, ENGLAND.

HEADLAMP FOR AUTOMOBILES.

Application filed March 20, 1924. Serial No. 700,541.

To all whom it may concern:

Be it known that we, WILLIAM EDWARD MARSHALL and PHILIP GEORGE PAGE McCULLOCH, both subjects of the King of Great Britain, residing at 32 Mortimer Street, London, England, have invented new and useful Improvements in Headlamps for Automobiles, of which the following is a specification.

10 This invention relates to improvements in head lamps suitable for automobiles.

The object of this invention is to provide a head lamp in which the beam therefrom whilst sufficiently illuminating the road will 15 not dazzle persons facing the lamp.

We have found that with head lamps having a paraboloidal reflector, the focal length of which is an inch and a quarter or less (this being the focal length of reflectors at 20 present commonly used), the rays reflected from the central portion of the reflector have a divergence at least four or five times greater than that of those proceeding from the outer portions thereof, this divergence being 25 due to the great difference between the maximum and minimum distances of the filament from the reflector.

We have also found that a reflector having a focal length of two inches reduces the 30 maximum divergence of the rays from the central portion of the reflector to less than twice that of the rays reflected from the outer portions.

In a head lamp constructed according to 35 our invention the reflector has a focal length of at least two inches and preferably three inches or more, and in order to obtain a beam of light, the vertical section of which is considerably smaller than the horizontal 40 section, so as to illuminate the sides of the road whilst at the same time keeping the top of the beam below the level of the eyes of an approaching pedestrian, we employ an incandescent electric lamp the filament of 45 which is arranged horizontally in a plane at right angles to the axis of the reflector, the bulb of the electric lamp being preferably spherical and the filament consisting preferably of a coil passing either through the geometrical centre of the bulb or situated in front thereof but not behind it.

The electric lamp we prefer to employ 50 comprises a spherical bulb having its filament situated a slight distance in front of the geometrical centre of the bulb (when in

position on the head lamp) this distance preferably being less than two millimetres and in no case greatly exceeding it, the object being to ensure that the whole of the filament is slightly in front of the centre of 60 curvature of the bulb.

The coil may be of considerable length, for example, three quarters of an inch or more.

With an electric lamp so constructed, the 65 comparatively large percentage of rays reflected back from the glass of the bulb itself on to the reflector are divergent to a slight extent only, and only those proceeding from the upper portion of the reflector therefore 70 rise upwards from the horizontal.

The electric lamp may be supported in an externally screw threaded holder, screwing into a threaded hole in the body of the lamp and held in position by an external lock nut, 75 the holder being of such length that the centre of the filament can be placed in the focus of the reflector, that is, outside the plane of the edge of the reflector.

In the accompanying drawings which illustrate the invention, Figure 1 is a vertical section with parts in elevation of a head lamp embodying the invention; Figure 2 is a plan view of the bulb and filament; and Figure 3 is a side elevation of the bulb and 85 filament of Figure 2.

1 is the lamp body, 2 a paraboloidal reflector having a focal length of three inches. 3 is a spring ring for keeping the reflector in position; 4 is an electric lamp holder having 90 an externally screw threaded portion 5, and 6 is a tapped socket in which the screw threaded portion 5 of the lamp holder engages; 7 is a lock nut retaining the holder 4 in position after correct adjustment. 8 is an 95 electric lamp having a spherical bulb (except for the pip). A—A is a line passing through the geometrical centre of the bulb. 9 is the filament coil situated in front thereof at a distance of 2 mm. therefrom, so that 100 the whole of the filament is slightly in front of the line A—A.

The arrangement shown provides means which allow existing lamp casing bodies to be readily fitted with a reflector of greater 105 focal length.

The use of a two inch reflector will reduce the maximum divergence of the rays from the central portion of the reflector to less than twice that of the rays reflected from the 110

outer portions, and with the use of a reflector of still greater focal length, this reduction is markedly larger.

Moreover, when employing an electric lamp as shown in Figures 2 and 3, a beam of light is produced having a lateral spread as large as is required, but in which the upward divergence is almost or entirely eliminated, such upward divergence being one of 10 the main causes of the dazzling effect in lamps as heretofore used.

What we claim is:—

15 A vehicle headlight comprising a casing, a substantially paraboloidal reflector within the casing, the focal length of which is greater than two inches, a socket supported axially of the reflector, and a light source in the

socket lying at the focus of the reflector, outside the plane of the edge thereof and within the boundary of the casing, said light source 20 comprising a substantially spherical incandescent lamp bulb having a long horizontal filament lying in front of the geometrical center of the bulb a distance less than two millimeters and in a plane at right angles to 25 the axis of the bulb and reflector whereby a laterally spread beam of light is produced with a minimum upward divergence.

In testimony that we claim the foregoing as our invention we have signed our names 30 this 10th day of March, 1924.

WILLIAM EDWARD MARSHALL
PHILIP GEORGE PAGE McCULLOCH.
